SAFETY HELMET

Daniel D. Webb, Birmingham, Mich., assignor to American Safety Equipment Corporation of Michigan, Southfield, Mich.

Filed Feb. 10, 1966, Ser. No. 1,007

Term of patent 14 years

(Cl. D3—13)

FIG. 1

FIG. 2

FIG. 3

FIG. 4

FIG. 1 is a front elevational view of a safety helmet showing my new design;

FIG. 2 is a side elevational view thereof, the side opposite being a mirror image thereof;

FIG. 3 is a front perspective view thereof; and

FIG. 4 is a front perspective view of a second embodiment of my design wherein the cord effect terminates on the modified visor.

I claim:

The ornamental designs for a safety helmet, as shown and described.
